UNITED STATES PATENT OFFICE.

THEODORE P. BRUNNER, OF LOS ANGELES, CALIFORNIA.

ESCAPE TRICK DEVICE.

Application filed November 24, 1925. Serial No. 71,150.

This invention relates to an escape trick device or a type of puzzle.

An object of the invention is to provide an improved trick or puzzle which can be used in exhibitions and consists essentially of the following: The exhibitor is shackled hand and foot and a plurality of rings are positioned about his arms and legs. Suitable tie devices connect the separate rings through one another and through the arms and legs respectively of the exhibitor. These tie devices are also fastened to a tie bar or other support and are so arranged that from appearances it seems impossible for the exhibitor to free himself from them. The trick device or puzzle is so constructed, however, that in performing certain operations or movements of the various rings, it is possible for the exhibitor to completely free himself from them without removing the shackles or severing or untying the tie devices. The invention can also be embodied in the form of a puzzle in which the arms or legs and the body and the shackles of the exhibitor can be represented by a suitable mechanical member.

With the foregoing and other objects in view which will be made manifest in the following detailed description and specifically pointed out in the appended claims, reference is had to the accompanying drawings for an illustrative embodiment of the invention, wherein:

Figure 1 is a perspective view illustrating the initial position of the trick device, as positioned upon the body of an exhibitor who is to free himself from the rings without removing the shackles or severing or untying the tie devices, and

Figs. 2 to 10 inclusive illustrate the various positions taken by the rings in performing the operations to remove them, these rings being illustrated in these figures as applied to a mechanical member which can be substituted for the arms or the legs of the exhibitor.

Referring to the accompanying drawings wherein similar reference characters designate similar parts throughout, the exhibitor has his hands and feet shackled as by shackles 11 and 12 respectively, these shackles being suitable hard-cuffs and the like which are so constructed that they can not be slipped over the wrists or ankles of the exhibitor. About the legs of the exhibitor are arranged a set of equally sized rings,

and in a similar manner another set of equally sized rings indicated at 13 are positioned about the arms. As both sets of rings are identical in construction and the operation of freeing them is the same, the following description will apply only to freeing the set of rings indicated at 13 from the arms.

The rings are four in number and are respectively indicated at 14, 15, 16 and 17. The ring 14 constitutes the end ring and a flexible tie device 18, such as a rope, cable, or chain, is tied to it adjacent its top and extends downwardly between the arms and is fastened to the tie bar or other stationary structure 19. A similar tie device 20 is fastened to the top of the ring 15 and extends downwardly between the arms and through the ring 14 and is then attached to the tie bar 19. The tie device 21 is fastened to the top of the ring 16 and passes through the ring 15 between the arms and is also tied to the tie bar 19. In a similar manner the tie device 22 is fastened to the top of the ring 17 and passes downwardly between the arms and through the ring 16 and is then tied to the tie bar.

In Fig. 2 the two arms of the exhibitor are indicated by parallel bars 23 which are connected at one end by a cross bar 24. The ends of the parallel bars 23 are enlarged or bent upwardly, as at 25, so that the shackle 11 cannot be slipped over the ends of the parallel bars. As a slight change in construction, the shackle 11 upon the member shown in Fig. 2 may have substituted for it a crossbar similar to the cross bar 24, it merely being essential that an elongated member be provided over which each of the rings is capable of passing and that there be an aperture formed through the member through which the rings are capable of being slipped or passed.

The first step in removing the rings is as follows: As shown in Fig. 2, the two end rings 16 and 17 are slipped over or off the ends of the arms of the exhibitor or off the ends of the parallel bars 23. The flexible tie devices 21 and 22 which are attached to these rings are merely drawn upwardly between the arms and rest upon the top of the shackle 11. In such a position the two rings 16 and 17 can be dropped through the aperture or between the parallel bars between the shackle 11 and the ring 15, which is one of the rings remaining on the

bars. When this has been done, the rings assume a position similar to that shown in Fig. 3, with the tie device 22 merely connecting the ring 17 through the ring 16. 5 The tie device 21 connects the ring 16 through the ring 15 to the tie bar 19. The rings 14 and 15 remain in their original positions. When in this position the ring 15 can be slipped off the ends of the parallel bars, as shown in Fig. 4, with its tie device 20 resting on top of the shackle 11. The ring 14 is also caused to slip off the ends of the arms or bars 23 and when in such position the tie device 20 will be passing through it and the tie device 18 will be connecting the ring 14 through the aperture to the tie bar. The ring 14 is then passed through the aperture so that it can slide down on the tie device 20 to a 10 position, as shown in Fig. 5, adjacent the tie bar. The ring 15 is then positioned over the parallel bars 23, as shown in Fig. 5, and the two rings 16 and 17 are then caused to pass upwardly through the 15 aperture or opening between the parallel bars 23 and the shackle 11 and the ring 15. After this has been done, they may be slipped onto the bars 23 over the shackle and caused to assume a position as shown 20 in Fig. 6. The next step is to withdraw the ring 17 from over the shackled ends of the bars and then drop it between the bars and between the shackle 11 and the ring 16, so that it may assume the position as illustrated in Fig. 7. The next step is to slip 25 the ring 16 off of the ends of the bars and also slip off the ring 15. After the ring 15 has been slipped off of the ends of the bars, it is caused to be dropped through 30 the aperture between the arms or bars and will slide down upon the tie device 21, assuming a position adjacent the tie bar 19 as illustrated in Fig. 8. The ring 16 is then slipped onto the bars as shown in Fig. 35 8, and the ring 17 is caused to pass upwardly between the bars and between the ring 16 and the shackle 11. After it has been so placed, it is slipped onto the bars assuming the position shown in Fig. 9. 40 From such a position both of the rings 16 and 17 are slipped off of the ends of the bars and can be caused to assume the position shown in Fig. 10, from which both of them may be simultaneously dropped between 45 the bars, and in this manner the member which is used for the substitute for the body, arms and shackle of the exhibitor is completely detached from the tie bar 19 without requiring the removing of the 50 shackle or the untying or severing of any of the tie devices. Furthermore, as all of the rings are of equal size, one ring cannot be passed through another.

When the trick is displayed as by an exhibitor 10, his arms and wrists are capable

of some movement, which is sufficient to shift the various rings through the necessary steps. When the hands of the exhibitor have been completely freed, he may then sit up and remove the set of rings from his legs in a similar manner. 70

It is possible for the rings to be again applied to the exhibitor or to the substitute member by shifting them through the various positions in the reverse manner. 75

From the above it will be appreciated that an improved trick device is provided wherein it appears that it is impossible by the arrangement of parts for the exhibitor to completely free himself, but that by making certain manipulations it is possible for this to be done. The tie devices have been illustrated upon the drawing as consisting of single ropes or cables for purposes of simplicity. It is contemplated within the scope of the invention to form these tie devices by using a single strand of rope or cable which is looped around the various rings and passed through the other rings and wrapped around the tie bar, which construction serves the same purpose as the single tie ropes 18, 20, 21 and 22 and causes the device to have a much more mystifying appearance, in that only two knots are required to fasten the single cable to the tie bar, one knot being at each end, and during the operation of the trick neither of these knots is loosened or the tie device severed. 85 90 95

It will be understood that various changes in the detail of construction may be made without departing from the spirit or scope of the invention as defined by the appended claims. 100

I claim:

1. An escape trick device comprising a tie bar, a plurality of equally sized rings, flexible tie means connecting one of the rings to the tie bar, and flexible tie means connecting each successive ring through its adjacent ring to the tie bar. 105

2. An escape trick device comprising a tie bar, a plurality of equally sized rings, flexible tie means connecting one of the rings to the tie bar, flexible tie means connecting each successive ring through its adjacent ring to the tie bar, an elongated member over which said rings are capable of passing, and means defining an aperture through said member through which the rings are capable of passing. 110 115 120

3. An escape trick device comprising a tie bar, a plurality of equally sized rings, an elongated member having an aperture arranged therethrough through which the rings are capable of passing, said member having said rings positioned thereabout, flexible tie means connecting an end ring through the aperture to said tie bar, and flexible tie means connecting each of the 125 130 135

other rings through the aperture and ring to the flexible tie bar, tie means connecting the third ring through the second 10 ring to the tie bar, and flexible tie means connecting the fourth ring through the third ring to the tie bar.

4. An escape trick device comprising a tie bar or equivalent support, four equally sized rings, flexible tie means connecting an end ring to the tie bar, flexible tie means connecting the second ring through the end

5 In testimony whereof I have signed my name to this specification.

THEODORE P. BRUNNER.
